(57) **CLAIM**

The ornamental design for an attachable biosignal sensing device as shown and described.

DESCRIPTION

FIG. 1 is a perspective view of an attachable biosignal sensing device, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded perspective view thereof; and,

FIG. 9 is a reference front elevation view thereof showing the attachable biosignal sensing device in a configuration use.

The broken lines in the drawings in FIGS. 8 and 9 show environmental structure or portions of the attachable biosignal sensing device that form no part of the claimed design.
